UNITED STATES PATENT OFFICE

HARRY W. KRAG, OF ST. LOUIS, MISSOURI, ASSIGNOR TO AMERICAN SHOE MACHINERY
AND TOOL COMPANY, OF ST. LOUIS, MISSOURI, A CORPORATION OF MISSOURI

SEWING MACHINE

Application filed March 14, 1932. Serial No. 598,541.

This invention relates to sewing machines, particularly to shoe sewing machines of the curved needle and awl type. The object of the invention is to provide a simple and compact arrangement of the stitcher head parts that will afford clearance between such parts and the shoe sole sufficient to permit shoe soles having narrow shanks to be shifted to a position to enable the needle and awl to engage such narrow shanks without forcing or distorting the shoe. Other objects are cheapness of construction, ease of assembly and fewness of parts. The invention consists in the parts and in the combinations and arrangements of parts hereinafter described and claimed.

In the accompanying drawing, which forms part of the specification and wherein like symbols refer to like parts wherever they occur,

Fig. 1 is a side view of a portion of a shoe sole sewing machine embodying my invention,

Fig. 2 is a front view of the parts shown in Fig. 1; and

usual spring means (not shown) for swinging said lever in a direction that will cause the presser foot 6 to yieldably engage the work. The presser foot lever 5 has an up-standing operating handle 10 fixed to its outer arm, whereby said lever may be manually operated to raise the pressure foot 6 and thus release the work.

In accordance with common practice, auxiliary means are provided for holding the presser foot 6 down upon the work. As

shown in the drawing, said means usually comprises an auxiliary presser foot arm 11 which is journaled at one end on a boss 12 formed on one side of the presser foot lever

5 concentric to the pivotal axis thereof and extends rearwardly above the rearwardly ex-

tending arm of said presser foot lever and is yieldably connected thereto by a stud 13.

Said stud is pivotally connected by a pivot

screw 14 to the rear arm of the presser foot lever 5 and extends upwardly through a boss 15 provided therefor on the auxiliary presser foot arm 11. The stud 13 is provided above

et 24 adapted to be engaged by two locking pawls 25, that are pivotally supported on a stud 26 secured to the stitcher head 1. One of the pawls 25 engages the ratchet 24 one-half a tooth higher than the other pawl; and both pawls are yieldably held in engagement with said ratchet by means of coil springs 27, which have one end secured to the stitcher head 1 and the other end bearing against the 10 respective pawls. By this arrangement, one of the pawls 25 will engage the ratchet 24 on the rear arm of the presser foot lever 5 to prevent upward movement of the presser foot 6 after the auxiliary pressure has been 15 applied thereto. When the cam lever 20 is swung downwardly to disengage the pawl 18 from the ratchet 21 on the auxiliary presser foot arm 11, the pawls 25 are disengaged from the ratchet 24 by the engagement of a cam 20 28 on said cam lever with arms 29 that extend rearwardly from the pawls 25.

Mounted on a horizontal shaft 30 fixed to the stitcher head 1 above the pivot pin or shaft 3 for the presser foot lever 5 is a thread 25 lifter lever 31 whose rearwardly extending arm is adapted to be actuated by means of the usual cam lever 32 and whose forwardly extending arm is provided with the usual thread lifter 33. One end of the thread lifter 30 lever shaft 30 is rigidly supported and braced by means of a brace member in the form of an arm 34, which is formed integral with the corresponding end of the presser foot lever pivot pin or shaft 3. The brace member 34 extends upwardly from the presser foot lever shaft 3 and is provided at its upper end with an opening adapted to receive and support the adjacent end of the thread lifter lever shaft 30, said end of said brace member 40 being split, as at 35, and provided with a screw 36 whereby it may be firmly clamped to said thread lifter lever shaft. As shown in Fig. 3, the front lower end portion of the thread lifter shaft support and brace member 34 of the pressure foot lever shaft 3 is beveled off, as at 37, thereby affording clearance between said end of said brace and the shoe sole A sufficient to permit shoe soles having narrow shank portions to be swung inwardly far enough to enable the needle (not shown) and the awl 9 to engage such narrow shank without forcing or distorting the shoe. 50

The pawls 18 and 25 are manually disengaged from the ratchets 21 and 24, respectively, on the presser foot lever 5 and auxiliary presser foot arm 11 by means of a hand release lever 38, which is located between said auxiliary presser foot arm and the brace 60 member or arm 34 and is pivotally secured to the inner face of the latter by means of a pivot screw 39. The upper arm of the hand release lever 38 forms a handle for swinging the same about the pivot screw 39, and the lower arm of said lever is connected by means

of a pivot screw 40 with the forward end of a pawl release arm 41 whose rear end is provided with fingers 42, 43 adapted to engage pins 44 and 45, respectively, on the pawls 18 and 25 to disengage them from the ratchets 21 and 24. A coil spring 46 has one end secured to the brace member or arm 34 of the presser foot lever shaft 3 and has its other end fixed to a pin 47 on the lower arm of the hand release lever 38 and serves to hold the fingers of the pawl release arm 41 in a position which will permit the pawls 18 and 25 to engage the ratchets 21 and 24, respectively, on the presser foot lever 3 and on the auxiliary presser foot arm 11. 70 75 80

The construction hereinbefore described is simple, economical and easy to operate and assemble. It is strong and durable and contains a minimum number of compactly arranged parts, it provides a one-piece member which pivotally supports the presser foot lever and the pawl release hand lever, it braces and supports the thread lifter lever shaft and it provides the shoe clearance required for sewing deep shank shoe soles. 90

What I claim is:

1. In a shoe sole sewing machine of the curved needle and awl type, a stitcher head, a presser foot lever, a thread lifter lever, a shaft mounted in said stitcher head and pivotally supporting said thread lifter lever, and a shaft located below the thread lifter lever shaft and pivotally supporting said presser foot lever, the presser foot lever shaft being provided at one end with an integral upwardly projecting arm that is secured to the corresponding end of the thread lifter lever shaft to support and brace the same. 95 100

2. In a shoe sole sewing machine of the curved needle and awl type, a stitcher head, a presser foot lever, a thread lifter lever, a shaft mounted in said stitcher head and pivotally supporting said thread lifter lever, and a shaft mounted in said stitcher head below said thread lifter lever and pivotally supporting said presser foot lever, the presser foot lever shaft being provided at one end with an integral upwardly extending arm that is secured to the corresponding end of the thread lifter lever shaft for supporting and bracing the same, the lower end portion of said arm being beveled off where it joins the presser foot lever shaft to provide increased shoe clearance. 110 115

3. In a shoe sole sewing machine of the curved needle and awl type, a stitcher head, a presser foot lever, a thread lifter lever, a shaft mounted in said stitcher head for pivotally supporting said thread lifter lever, a shaft located below the thread lifter lever shaft for pivotally supporting said presser foot lever, the presser foot lever shaft being provided at one end with an integral upwardly projecting arm that is secured to the corresponding end of said thread lifter lever 120 125 130

shaft for supporting and bracing the same, and a pawl release lever pivotally supported on the integral arm portion of said presser foot lever shaft.

5 4. In a shoe sole sewing machine of the curved needle and awl type, a stitcher head, a presser foot lever, a thread lifter lever, a shaft mounted in said stitcher head for pivotally supporting said thread lifter lever, a shaft located below the thread lifter shaft for pivotally supporting said presser foot lever, the presser foot lever shaft being provided at one end with an integral upwardly projecting arm that is secured to the corresponding end of said thread lifter lever shaft for supporting and bracing the same, and an auxiliary presser foot arm cooperating with said presser foot lever and pivotally mounted on the same for swinging movement about the axis of said presser foot lever shaft.

5. In a shoe sole sewing machine of the curved needle and awl type, a stitcher head, a presser foot lever, a thread lifter lever, a shaft mounted in said stitcher head for pivotally supporting said thread lifter lever, a shaft located below the thread lifter shaft for pivotally supporting said presser foot lever, the presser foot lever shaft being provided at one end with an integral upwardly projecting arm that is secured to the corresponding end of said thread lifter lever shaft for supporting and bracing the same, an auxiliary presser foot arm cooperating with said presser foot lever and pivotally mounted on the same for swinging movement about the axis of said presser foot lever shaft, the corresponding ends of said presser foot lever and said presser foot arm being provided with ratchets, pawls pivotally supported on said machine and cooperating with said ratchets, and a lever journaled on the integral arm of said presser foot lever shaft for disengaging said pawls from said ratchets.

Signed at St. Louis, Missouri, this 11th day
45 of March, 1932.

HARRY W. KRAM.
